(57) **CLAIM**

We claim the ornamental design for a wand for a cleaning appliance, as shown and described.

DESCRIPTION

FIG. 1 is a top, front and right-side perspective view of a wand for a cleaning appliance showing our new design;

FIG. 2 is a top plan view thereof;

FIG. 3 is a bottom plan view thereof;

FIG. 4 is a left-side elevation view thereof;

FIG. 5 is a right- side elevation view thereof;

FIG. 6 is a front elevation view thereof; and,

FIG. 7 is a rear elevation view thereof.
